SPORT SHOE

William J. Cohen, Boston, Mass., assignor to CITC Industries, New York, N.Y.

Filed Oct. 24, 1972, Ser. No. 300,130

Term of patent 14 years

U.S. Cl. D2—310   Int. Cl. D2—04

Fig. 5

Fig. 6

Fig. 3

Fig. 7

Fig. 8

Fig. 4

FIG. 1 is a side perspective view of a sport shoe adapted to be worn on the right foot showing my new design;

FIG. 2 is an enlarged front view thereof;

FIG. 3 is a top plan view;

FIG. 4 is a rear view;

FIG. 5 is a side perspective view of the left sport shoe with the ornamentation thereon modified as shown;

FIG. 6 is an enlarged front view thereof;

FIG. 7 is a top plan view; and

FIG. 8 is a rear view.

I claim:

The ornamental design for a sport shoe, substantially as shown and described.
